UNITED STATES PATENT OFFICE.

HERVY P. WICKES, OF CHARLEROI, PENNSYLVANIA.

BASEBALL GAME.

Application filed May 14, 1921, Serial No. 469,474. Renewed June 16, 1923.

To all whom it may concern:

Be it known that I, HERVY P. WICKES, a citizen of the United States, residing at Charleroi, in the county of Washington and State of Pennsylvania, have invented certain new and useful Improvements in Baseball Games, of which the following is a specification, reference being had to the accompanying drawings.

10 This invention relates to game apparatus, and particularly to a baseball game.

The general object of the invention is to provide a game apparatus of this character including a puppet or figure simulating a batter and carrying a bat, and means whereby the figure with the bat may be retracted against the force of a spring and then released to simulate the action of batting, and to provide means whereby a ball may be 20 simultaneously shot upward in front of the bat so that if the bat strikes the ball, the ball will be driven by the bat over the field.

A further object is to provide a baseball game of this character with very simple and 25 effective means for actuating the batter and throwing up the ball.

And a further object is to provide a game of this character including figures adapted to be supported in a vertical position at the 30 end of the field, which figures may be struck by the ball under the action of the bat and knocked over.

Another object is to provide a game of this character wherein the figures are so 35 mounted that when struck by the ball they will remain tipped over to indicate the score made by the player.

Still another object is to provide a baseball game comprising a board laid off or 40 painted to represent a baseball field and diamond, a doll or figure representing the batter and carrying a bat, and mounted for oscillating movement, means for projecting the ball upward in advance of the bat so 45 that the batter may strike the ball, and a section adapted to be disposed in a vertical position and having as a background the representation of a grandstand, and having mounted thereon a plurality of figures 50 adapted to be struck by the ball and knocked over thereby, the batter being removed from the section representing the playing field, and the section representing the playing field and the section representing the grand- 55 stand with its figures being adapted to be

nested in each other so that the apparatus may be packed in a box.

Other objects will appear in the course of the following description.

My invention is illustrated in the accompanying drawings, wherein:—

Figure 1 is a top plan view of a game apparatus constructed in accordance with my invention;

Figure 2 is a transverse section across the 65 base forming the playing field and an elevation of the section 30;

Figure 3 is a top plan view of the mechanism for actuating the batter;

Figure 4 is a fragmentary section through 70 the base showing an end view of the actuating mechanism;

Figure 5 is a section through one of the figures 32 on the part 30;

Figure 6 is a section through the part 30 75 showing a target 33;

Referring to these drawings, it will be seen that the playing field is indicated on a board 10. The upper face of this board is painted or otherwise formed to indicate the 80 playing field and on this board is shown the usual diamond A with the usual bases, and at the plate B there is formed an opening 11. The board 10 is disposed in spaced relation to a baseboard 12, and a surrounding wall 13 separates the boards 10 and 12 from each other so as to leave a space between the two parts. This surrounding wall may be interrupted at two points, as at 14, or entirely closed.

Rotatably mounted in the board 10 and extending downward into a bearing in the board 12 is what may be termed a vertical shaft 15, that portion of the shaft between the boards 10 and 12 being square. This 95 shaft at its upper end is formed to provide a semi-circular socket 16. The figure 17 or batter has a downwardly extending stub 18 that fits within the semi-circular opening or socket. This figure 17 carries a bat 19. 100 Passing through the end wall of the casing is a rod 20 which is formed with a shoulder 21, this rod 20 being rotatable and reciprocal. A spring 22 bears at one end against the shoulder 21 and at the other end against the wall 13, and the outer end of the rod 20 is provided with a handle 23 which is preferably square in cross section. The rod 20 carries at its inner end a longitudinally extending wire finger 24 which is angularly 105 110

bent at its extremity, as at 25, and attached to the bottom board 12 and extending upward beneath the rod 24 is a relatively wide leaf spring 26, the extremity of which is disposed immediately beneath the countersunk opening 11.

The shaft 15 is pivotally and hingedly connected to the rod 21 by the hinge leaves 27 and 28, the leaf 27 being an ordinary hinge leaf, and attached to one flat face of the squared portion of the rod 15, while the hinge leaf 28 is perforated at its extremity and rotatably engaged with the end of the rod 15 by means of the headed pin 29. It will thus be obvious that the rod 20 may be rotated without materially affecting the shaft 15, but that when the rod 20 is pulled by the knob 23 or is projected by the spring 22, the shaft 15 will oscillate. When it is desired to project the ball, the ball C is placed in the countersunk opening 11, the ball seating in the countersink of this opening. At this time the angular terminal end 25 is disposed in a horizontal plane and the batsman stands with the bat extending over the ball or in line therewith. If now the knob 23 be pulled back against the action of spring 22, the angular end 25 of the rod 24 will be drawn over the spring 26 and at the same time the shaft 15 will be oscillated in a direction to cause the batter to carry the bat away from the ball. When the rod 20 has been fully retracted, if it be turned in a clockwise direction by the knob 23, the angular terminal end 25 will turn downward, carrying the spring 26 downward, and if now the knob be suddenly released, the spring 22 will cause the rod 20 to spring forward, releasing the spring 26 from the finger 25. The batter will turn with the shaft 15 in a direction to carry the bat toward the ball and at the same time the spring 26 will fly upward and, striking the ball, cause the ball to be projected upward across the path of movement of the bat. If the bat strikes the ball, the ball will be projected upward and forward over the field.

The playing field formed by the members 10 and 12 and the marginal board 13 forms the base of a box, the top of the box being formed by a cover section 30. The inside face of the cover section is painted or otherwise formed to simulate the grandstand of a ball park, and extending longitudinally along this cover section are a plurality of rails 31, these rails having horizontal upper faces, and hinged upon these rails are a plurality of more or less comical figures 32, these figures being hinged upon the rails 31 so that they may tip over backward when struck, as illustrated in Figure 5. All of the figures may be of the same character or the figures may be of different characters, and I have illustrated on two of the rails circular targets 33 which are also hinged to

the corresponding rails so that when struck they will be tipped backward, and when these circular targets are struck by a ball, the count given to the player is greater than when any of the other figures are struck by the ball. It will be obvious that the figures may have different counts or the same count as desired.

In playing this game, the base section formed by the boards 10 and 12 is disposed horizontally upon the table, while the section 30 is disposed vertically at the end of the "field." The ball being placed upon its seat 11, each player rotates the handle or knob 23 and retracts the knob so as to retract the bat and retract the spring 26, and then upon a release of the knob, the batter will strike at the ball and the ball will be projected upward across the path of movement of the bat. The object of the game is to send the ball into the grandstand and, if possible, strike any one of the figures 32 therein, and better yet even, one of the targets 33. While various rules may be adopted for playing the game and while the figures or targets 32 and 33 might carry thereon indications whereby a player piece might be shifted around the bases of the baseball field to thereby count runs, hits, etc., yet I contemplate that each player shall have three strikes, that is three chances to hit the ball, these three strikes counting one inning. Each time a target 32 is hit it counts for one run and if the ball is knocked over the top of the section 30 it will also count as one run. If the ball should strike either one of the targets 33 it counts as three runs. While nine innings will ordinarily make a full game, yet obviously any number of innings may be played.

I do not wish to be limited to the particular manner in which the targets are mounted, the particular arrangement of these targets, nor to the use of my device as a "baseball" game, as obviously it might be used for games of other characters, and that the targets may be changed in many ways without departing from the spirit of the invention.

I claim:—

1. A game apparatus of the character described comprising a playing board having thereon an upright figure holding a bat, the bat being oscillatable in an approximately horizontal plane, resilient means urging the bat to a normal position, manually operable means for retracting the bat against the action of the resilient means and releasing the bat, means for simultaneously projecting a ball in a direction parallel to the figure and across the path of movement of the bat as it is acted on by the resilient means, and a support on the board, the ball projecting means being between said support and the bat when the bat is retracted, said sup-

port having a series of members mounted thereon in a line transverse to the path of movement of the ball when projected by the bat and constituting targets against which the ball may be projected when struck by the bat.

2. A game apparatus including a playing board, a figure mounted thereon for rotative oscillation and carrying a bat, the upper face of the board being formed with a concavo-convex ball seat disposed approximately below the normal position of the bat and having an opening extending to the under face of the game board, resilient means urging the figure to a normal position with the bat disposed above the ball seat, a resiliently actuated member disposed below the ball seat and adapted when in its normal position to operatively strike the lower face of a ball disposed in said seat and project the ball upward, and manually operable means whereby the figure and spring actuated means may be retracted and then suddenly released to thereby project the ball upward from the ball seat across the path of movement of the bat.

3. A game apparatus including a playing board, a figure mounted thereon for rotative oscillation and carrying a bat, a spring urging the figure to a normal position, the board being formed with a ball seat in its upper face approximately below the normal position of the bat, a resiliently actuated ball striker disposed below the ball seat and adapted to strike the ball when retracted and released, and manually operable rectilinearly movable and axially rotatable means whereby the figure may be retracted against the action of the spring, said means when pulled in one direction retracting the figure and when axially rotated retracting the ball striking device, said means when released and retracted by the spring of the figure releasing the ball striking device to permit the simultaneous movement of the batter and projection of the ball.

4. A game apparatus of the character described comprising a player field, a figure mounted thereon for oscillating movement in a horizontal plane and carrying a bat, the board being provided with a ball seat below the bat, a spring disposed below the ball seat and when released adapted to engage the ball and project it upward, a spring urging the figure to its normal position, and means for retracting the figure and simultaneously retracting the first named spring and then simultaneously releasing the figure and spring.

5. In a game apparatus, a player board, an upright figure mounted thereon for oscillating movement in a horizontal plane, a shaft extending below the player board and carrying said figure, the player board being formed with a ball seat and be-

low the normal position of the bat of said figure, a leaf spring disposed below the board and extending across the ball seat, a longitudinally movable rod having a handle disposed below the player board and having operative engagement with said shaft to cause the oscillation of the shaft and the retraction of the bat when the rod is pulled, a string urging the rod forward and the figure into a normal position, and means carried by said rod acting to retract the ball projecting spring when the rod is retracted and release said ball projecting spring when the rod is released.

6. In a game apparatus, a player board, an upright figure mounted thereon for oscillating movement in a horizontal plane, a shaft extending below the player board and carrying said figure, the player board being formed with a ball seat and below the normal position of the bat of said figure, a leaf spring disposed below the board and extending across the ball seat, a longitudinally movable rod having a handle disposed below the player board and having operative engagement with said shaft to cause the oscillation of the shaft and the retraction of the bat when the rod is pulled, a spring urging the rod forward and the figure into a normal position, said rod having an extension extending across the leaf spring, the extension being angularly bent at one end whereby when said rod is retracted to reproductively oscillate the figure and the rod is rotated, the angular end of the extension will engage the leaf spring to retract it, the release of the rod releasing the figure to permit its oscillation in a reverse direction and the simultaneous release of the leaf spring.

7. A game apparatus including a player board having thereon a ball seat opening to the under face of the board, a shaft extending vertically through the board, an upright figure mounted upon said shaft and having a bat, a leaf spring disposed below the player board and having its free end disposed below the ball seat, a longitudinally movable and rotatable rod mounted below the player board, operative connections between said rod and the shaft whereby the shaft may be oscillated in one direction upon a retraction of the rod, said connection permitting the rod to be axially rotated without affecting the shaft, a spring resisting the retraction of said rod, said rod having an extension having an angular extremity adapted when the rod is retracted to engage with the leaf spring and when the rod is rotated after being retracted to depress the leaf spring, the release of the rod releasing said leaf spring.

8. A game apparatus including a player board having thereon a ball seat opening to the under face of the board, a shaft extend-

ing vertically through the board, an upright figure mounted upon said shaft and having a bat, a leaf spring disposed below the player board and having its free end disposed below the ball seat, a longitudinally movable and rotatable rod mounted below the player board, a spring resisting the retraction of the rod, a hinge leaf mounted upon the shaft, a second hinge leaf hinged to the first named leaf and having an aperture, a pin rotatively engaging the second named leaf with the end of said rod, an extension carried by the rod and projecting beyond its

point of engagement with the shaft, said extension being angularly bent, a retraction ¹⁵ of the rod carrying the angular end of the extension over said leaf spring, a rotation of the rod causing the depression of said spring, and a release of the rod permitting the rotation of the shaft under the action ²⁰ of the first named spring and the release of said leaf spring to project the ball across the path of movement of the bat.

In testimony whereof I hereunto affix my signature.

HERVY P. WICKES.
